UNITED STATES PATENT OFFICE.

ROMAN B. BUKOLT, OF STEVENS POINT, WISCONSIN.

CHILD'S PEDALING-CAR.

1,383,070.

Specification of Letters Patent. Patented June 28, 1921.

Application filed May 15, 1919. Serial No. 297,427.

To all whom it may concern:
Be it known that I, ROMAN B. BUKOLT, a citizen of the United States, residing at Stevens Point, in the county of Portage and 5 State of Wisconsin, have invented certain new and useful Improvements in Children's Pedaling-Cars; and I do declare the following to be a full, clear, and exact description of the invention, such as will enable others 10 skilled in the art to which it appertains to make and use the same.

My invention has for its principal object to provide a child's pedaling car which may be constructed easily and inexpensively and 15 sold at a comparatively low price, yet one which will be highly desirable, for exercising both the arms and legs.

In carrying out the above end a central longitudinal beam is employed having lateral extensions at its rear end which are mounted on the rear axle, and further objects are to construct said extensions in a 20 novel manner to form bolster brackets supporting the beam from the axle, and to secure a seat-board to said extensions and beam in a manner to brace them relatively.

A vertical bearing is carried by the front end of the central beam and a steering post is mounted in said bearing to carry the front 30 wheel, a further object of the invention being to provide a novel means for forming a fork for the front wheel and for also supporting said bearing.

With the foregoing objects in view, the 35 invention resides in the novel construction and arrangement of parts hereinafter fully described and claimed, and shown in the accompanying drawings.

Figure 1 is a side elevation of a pedaling 40 car constructed in accordance with my invention.

Fig. 2 is a top plan view.

Fig. 3 is a rear elevation with parts in section.

Fig. 4 is a front elevation partly in section.

Fig. 5 is a vertical section on the plane of line 5—5 of Fig. 1.

Fig. 6 is a horizontal section on the plane 50 indicated by line 6—6 of Fig. 1.

Fig. 7 is a perspective view of one of the pitmen.

Fig. 8 is a perspective view of one of the bolster brackets.

55 In the drawings above briefly described, the numeral 1 designates a central longitu-

dinal beam standing on edge in a vertical plane and having lateral extensions 2 at its rear end, said extensions being by preference in the form of inverted L-shaped blocks 60 of wood forming bolster brackets which support the rear end of the car from a cranked rear axle 3. The lower ends of the brackets 2 are provided with bearings 4 mounted on the axle 3 adjacent the two rear wheels 5, 65 while the upper ends of the brackets are spaced apart. The rear end of the beam 1 is received between the upper ends of the brackets 2 and is secured between said brackets by dowel pins 6 or by any other 70 preferred means. A horizontal seat-board 7 rests on the upper edges of the brackets 2 and on the rear end portion of the beam 1 and by any preferred means is secured to these parts, thus not only performing the 75 function of a seat but serving to relatively brace the brackets and beam. Dowel pins 8 are shown for securing the seat in place, but other adequate means could be employed.

The front end of the beam 1 by preference inclines upwardly and rearwardly to a slight extent and carries a vertical bearing 9, said bearing comprising a channel shaped metal plate which straddles the front end of the beam and is secured thereto by rivets 85 or the like 10. A steering post 11 passes through the bearing 9 and carries a front wheel 12 at its lower end while its upper end is provided with an appropriate handle 13 which may be of any desired type. To 90 support the bearing 9 upon the steering post 11 and at the same time to provide a fork on which the front wheel is mounted, I secure a pair of preferably metal arms 14 to opposite sides of said steering post under 95 the bearing, by rivets or the like 15. The bearing 9 rests on the upper ends of the arms 14 and wheel 12 is mounted between said arms upon a rivet or other suitable device such as 16. The wheel 12 is preferably 100 of wood, as are also the wheels 5, and the hubs of all of said wheels are preferably provided with suitable bushings 17. All of the wheels may be rubber tired if desired, but I prefer to equip only the rear wheels 5 105 with such tires as indicated at 18.

By providing the metal arms 14 to support the bearing 9, very little friction exists to retard steering of the car, and obviously this construction is of great advantage in manufacture, due to its extremely simple and inexpensive nature. To prevent

the bearing 9 from sliding upward on the steering post a screw or the like 19 may be driven in said post at the upper end of the bearing.

5 For operating the axle 3, I provide a pair of forwardly extended pitmen 20 connected at their rear ends to the cranks of said axle by bearings 21, while suitable stamped metal clips 22 are employed for pivoting the front 10 ends of said pitmen to levers 24 which depend from the front end of the beam 1. The upper ends of the levers 24 are fulcrumed at 25 at opposite sides of the beam 1 by means of a single pivot pin and the lower 15 ends of said levers are provided with lateral foot pedals 26 each preferably formed of a cylindrical wooden block riveted to the lever. Any suitable means such as a yoke 27 on the axle 3 may be employed for locking 20 one wheel to said axle so that the machine will be propelled when the pedals are operated.

By constructing the device in or approximately in the manner shown and described, 25 it may be easily and inexpensively manufactured, principally of wood, although metal parts are necessary at some points. Particular emphasis is laid upon the central beam 1 with its lateral extensions 2, the seat- 30 board 7 secured to these parts and relatively bracing them, the bearing 9 and steering post 11, and the arms 14 secured to said post to support said bearing and to provide a fork for the front wheel. All of these features contribute to inexpensive manufacture 35 and to the successful operation of the device.

The child obviously sits upon the seat 7, steers with his hands by grasping the handle 13, and propels the car by operating 40 the pedals 26 with his feet. The device not

only affords a great deal of amusement, but is an effective exerciser, bringing into play all of the leg, arm and back muscles.

Since excellent results are obtained from the exact details disclosed, they are preferably followed, but within the scope of the invention claimed numerous minor changes may well be made.

I claim:

1. A child's car comprising rear wheels 50 and a cranked axle therefor, inverted L-shaped bolster brackets having bearings on their lower ends mounted on said axle between the axle cranks and the wheels, the upper ends of said brackets extending inwardly toward each other above the cranks and terminating in spaced parallel relation, a flat longitudinal beam standing on edge and having its rear end received between said spaced bracket ends, dowels passing 55 through said beam and into said bracket ends, a seat-board secured on said brackets and the rear end of said beam and serving to tie said beam and brackets together, and steering and supporting means for the front 60 end of said beam.

2. A child's car comprising a central longitudinal beam having a seat, a channel shaped metal plate straddling the front end of said beam and forming with said beam a vertical bearing, a steering post passing 70 through said bearing, metal arms secured to said post under said bearing and forming a fork, the upper ends of said arms supporting said bearing, a front wheel mounted between said arms, and a handle on the upper 75 end of said steering post.

In testimony whereof I have hereunto set my hand.

ROMAN B. BUKOLT.
